GARMENT OR IRONING PRESS

Ernest Davis, Syracuse, N. Y., assignor to The Prosperity Company, Inc., Syracuse, N. Y., a corporation of New York

Application January 16, 1931, Serial No. 509,059
Renewed October 17, 1933

14 Claims. (CL. 68—9)

This invention pertains to a garment or ironing press having coacting press jaws consisting of a head which is swingable upwardly and rearwardly of the other and fixed jaw or buck so that a clear view of the work upon the fixed jaw is obtainable. The invention relates particularly to the operating mechanism by which the swingable jaw is moved away from the other jaw as well as to the particular frame construction for supporting such mechanism.

It is an object of the invention to construct a garment or ironing press in which the movable jaw or head is raised and lowered substantially vertically to and from the buck or fixed jaw in order to obtain jaw compression without relative sliding motion between the jaws and in which the movable jaw is swingable rearwardly to clear the work with novel operating mechanism to produce the movement.

Another object of the invention is to produce a novel construction of mounting for a jaw-carrying member which carries the movable jaw or head so that the member will have more rigid and improved support upon the press frame.

Another object is to devise a new and novel operating mechanism for a garment or ironing press.

Other objects of the invention will be more apparent from the following description, taken in connection with the accompanying drawings, in which:

Figure 1 is a rear view of the press in open position with certain portions thereof in section taken along the line 1—1 of Figure 2 to more clearly show the operating interconnection between the parts.

Figure 2 is a section of the press taken on line 2—2 of Figure 1 showing the press in open position with a motor means and other operating mechanism whereby the jaw-carrying member swings the press head away from and rearwardly of the fixed jaw or buck.

Figure 3 is a section through the press taken on line 3—3 of Figure 1 with the press approximately in closed position at the end of the closing movement of the press and at the beginning of the jaw compression or pressure movement.

Figure 4 is a side view of the press with a portion thereof in section showing the press and press jaws in compression position with the movable jaw or head pressing against the fixed jaw or buck.

Figure 5 is a section taken on line 5—5 of Figure 1 showing the position of the operating mechanism and jaw-carrying member in full open press position.

Figure 6 is a section taken on line 6—6 of Figure 4 showing details of the frame construction and the manner in which the jaw-carrying member is mounted thereupon, so that the head carried by the member is swingable towards and away from the fixed jaw or buck.

The garment or ironing press of the invention includes a stationary jaw or buck and a movable jaw or head which comprise the coacting press jaws. The movable head is carried upon a jaw-carrying member which is given a swinging movement upwardly away from the stationary buck and rearwardly clear thereof in order to enable the operator to obtain a clear vision of the work upon the buck without interference from the head. The operating mechanism by which the movable head is swung away from the stationary buck comprises the principal feature of the invention, although details of the frame supporting the press and the mechanism for supporting the jaw-carrying member constitute some of the more detailed features of the invention.

The press is provided with a frame 10 carrying a pedestal 11 to support a stationary jaw or buck 12. The movable jaw or head 13 is mounted upon a jaw-carrying member 14 which member is given a swinging movement in order to carry the movable jaw or head 13 over the stationary jaw or buck 12 and subsequently give it a vertical movement to obtain jaw compression. The reverse of these movements occurs upon opening of the press. The buck 12 and movable head 13 comprise the coacting jaws of the press.

The jaw-carrying member 14 is provided with a pair of guide pins 18 carrying rollers 19 which engage within a slot 20 in each side of the frame 10. The guide pins 18 with their rollers 19 working in the slots 20 provide means for guiding the jaw-carrying member 14 and preferably for the lower end thereof and assist in controlling or directing the movement of the head 13 and jaw-carrying member 14. The jaw-carrying member also pivots about the guide pins 18 as well as being guided thereby. Any other form or type of guide means is contemplated by the invention such as a radius link construction which is equivalent in function and operation to the preferred construction described herein.

The jaw-carrying member 14 carries a pair of bearings 23 which provide compound motion pivots 24 in axial alignment for the jaw-carrying member which are spaced from the guide pivots formed by the guide pins 18. The compound motion pivots 24 are preferably positioned in the central part of the jaw-carrying member. Each

of the compound motion pivots 24 is mounted in its bearing 23 so that each end projects beyond its respective bearing thereby forming outer ends which project outside of the jaw-carrying member 14 and inner ends which project towards each other within the jaw-carrying member.

Radius links 25 are secured to the outer end of each of the pivots 24 and are pivotally mounted in the frame 10 upon a frame pivot 26. The inner ends of each of the compound motion pivots 24 are secured to radius links 27 which are pivotally carried upon a frame pivot 28 mounted in a central bearing 29, shown more clearly in Figure 6, the bearing being carried by a supporting flange 30 extending outwardly from the side and top of the frame 10 to bring the bearing 29 into alignment with the pivots 26. The frame pivots 26 and 28 are in direct alignment and for all purposes function as one and the same pivot for the radius links. The radius links 25 and 27 with the compound motion pivots 24 and the frame pivots 26 and 28 comprise radius link means which pivotally carry the jaw-carrying member 14. A simpler construction for the radius link means is suitable but does not afford the rigidity and smoothness of operation that is obtained by the radius link means described herein.

The jaw-carrying member 14 carries a pair of spaced flanges 31 which give the jaw-carrying member rigidity and enable it to pass between the radius links 25 and 27 which are spaced apart to permit this construction. There is therefore a radius link on each side of each bearing 23 or upon each end of each compound motion pivot 24 which reduces wobble in the press and results in a smooth operating press and assures the head and buck coming into proper pressing alignment.

The jaw-carrying member 14 has therefore spaced pivots comprising the guide pivots or pins 18 and the compound motion pivots 24, and upon the latter are mounted the links 25 and 27 which form radius link means for supporting or carrying the jaw-carrying member and swinging it and the head to open and close the press. The guide pivot 18 spaced from the compound motion pivots 24 of the jaw-carrying member 14 is preferably guided in its movement by the groove 20 which may be of any desired construction and the curve taken by the groove 20 is designed to enable the head to have a substantially vertical movement during the approach and removal of the head from the buck or during jaw compression. In addition, the groove 20 cooperate with the radius link means to give the head 13 a rapid rearward and forward movement when opening and closing the press.

The radius links 27 have an extension or actuating means which is shown as a cam arm 35 in which a cam groove or slot 36 is provided consisting of a rapid-movement or high-speed portion 37 and a compression or pressure portion 38 disposed at an angle to the high-speed portion 37. The high-speed portion 37 is in fact and in effect a shoulder which is engaged by the force applying means and is moved at the same rate of speed or substantially at the same rate of speed as the power means. It is pointed out here also that the high-speed portion 37 of the cam slot 36 is also nearer to the frame pivot 28 upon which the cam arm is pivotally mounted and the compression or pressure portion 38 is more distant from the pivot 28 than the rapid-movement portion 37. The purpose of the angular relation of the two portions 37 and 38 of the cam groove 36 is the effect of their distance from the frame

pivot 28 and the manner in which they function will be described in greater detail hereinafter. The cam groove or slot 36 comprises cam means which is connected to the radius link means, although in its preferred form the cam means is integral with the radius link means. Similarly, a pair of cam grooves 36 is shown to improve the smoothness and uniformity of operation, but it is clear that at least one such cam or actuating means will operate the press.

A cam roller 41 or force applying means engages within the cam slot 36 and is carried upon a roller shaft 42 mounted in a cross head 43. The cam means with its slot 36 in receiving the cam roller 41 is also termed a force receiving means since the operating face of the cam slot engages or receives the force delivered by the cam roller or power means. The cross head 43 is carried upon a piston rod 44 operatively connected to a piston 45 working in a cylinder 46. The cross head 43 is guided in its movement by the slide 47 which is attached to the frame 10 upon a fixed pin 48. The motor cylinder 46 is mounted at its lower end upon a fixed pin 49 carried by a pedestal 50 secured to the frame 10. It will be noted that the motor cylinder 46 and the slide 47 are rigid structures secured at both ends to the frame so that the motor or operating means is fixed in position and does not pivot. Motor springs 51 have one end thereof fastened to the ends of the roller shaft 42 and the other end secured to a lug 52 upon the base of the frame 10.

The actuating means 35 moves in a path or direction of movement which is away from or at an angle to the path of movement of the roller 41 at least during the latter part of its movement. Because these parts of movement diverge during the power stroke, the roller 41 moves out of or away from engagement with the high speed portion 37 of the cam slot 36 and engages the camming portion 38 of the slot for a slower compression movement. It should be noted that so long as the roller 41 engages the end of the high speed portion of the cam slot 37, the actuating means 35 moves at or substantially at the same rate of speed as the roller. There is during this movement some mechanical ratio change taking place as a consequence of a minor change in the radial distance between the roller and the pivot. This is wholly a radial change. When, however, the roller engages the cam slot or cam portion 38 then there is not only a more rapid mechanical ratio change of radial distance from the pivot 28, but there is also a camming action which is more important in converting a long piston stroke into a heavy compression stroke of the movable jaw.

An operating or press opening spring 54 is secured at one end to a projection 55 carried by the frame 10 and its other end is secured to a projection 56 carried by the jaw-carrying member 14. This spring pulls upwardly on the jaw-carrying member and swings it to open press position when the fluid pressure is released from the lower side of the piston 45 of the motor means. Fluid pressure applied to the piston 45 through the fluid supply line 58 closes the press which remains closed so long as the fluid pressure is applied to the piston. Upon exhausting the fluid pressure on the piston 45 the spring 54 opens the press. The spring and the motor means with its connections to the cam means or slot 36 comprise the operating means for opening and closing the press. The roller 41 with the motor

means and the associated mechanism are then included in the operating means and may be described generally as means engaging the cam means to close the press.

5 The operation of the press from open press position as shown in Figure 2 is as follows. A charge of air is directed into the bottom of the cylinder 46 of the motor means through the fluid supply pipe 58 by valve means known to the art, whereupon the piston 45 is forced upwardly and carrying the piston rod 44, the cross head 43 and the cam rollers 41 upwardly therewith. The cross head slide 41 and the rigid anchorage of the motor means to the frame brings about an upward straight line movement to the cam rollers 41 as guided by the cross head 43 sliding in the straight cross head slide 41. Upward movement of the cam rollers 41 swings the arms 35 or the cam means and the radius link means including radius links 25 and 27 in a counter-clockwise direction about the frame pivots 26 and 28 which swings the jaw-carrying member 14 upward on the compound motion pivots 24 over the buck 12, the lower end of the jaw-carrying member 25 being controlled in its movement by the guide means or guide pins 18 moving downwardly in the slots 20 until the press assumes the position shown in Figure 3. In this position the press head is at the end of the press closing movement and at the beginning of the movement which brings about jaw compression.

Continued upward movement of the cam rollers 41 brings the head 13 substantially vertically downward upon the buck 12 because the radius links 27 are substantially in a horizontal position which gives the compound motion pivot 24 a substantially vertical movement. The guide pins 18 working in the guide slots 20 control or direct the movement of the head so that the press head has a substantially true vertical downward movement during the compression stroke. The slight curvature at the bottom of the guide slot 20 cooperates with the radius link means to give the head 13 the vertical downward compression movement. Upon releasing the fluid pressure upon the piston 45, the piston springs 51 pull the piston 45 and cam roller 41 downwardly and the springs 54 pull the jaw-carrying member 14 upwardly thereby opening the press.

50 It has previously been mentioned that the portion 37 of the cam slot 36 is a high-speed portion and is so termed because it brings about a rapid movement of the head and that the portion 38 of the cam slot extending at an angle from the high-speed portion 37 is a compression portion so termed because a heavy compression force between the jaws is produced thereby. The two characteristics of the cam slot 36 described above are obtained because the high-speed portion 37 of the cam slot is adjacent to the frame pivot 28 upon which the cam means is pivotally mounted and, consequently, in open press position as shown in Figure 2 and in particular in Figure 5, with the cam rollers 41 at the end of the cam slot 36 nearest to the frame pivot 28, a small or unit movement of the cam roller 41 upwardly will produce a relatively considerable rotation of the radius links 27 and a considerable movement of the press head 13. It will be clear, therefore, that as the cam roller 41 continues its upward movement and moves farther along the high-speed portion 37 of the cam slot 36 or farther away from the frame pivot 28, the cam means rotates relatively less for a unit extent of movement of the cam roller 41 and the jaw-car-

rying member 14 will also move at a relatively slower rate, yet the movement of the jaw-carrying member and the head will be rapid because of the short radius through which the rollers are working as determined by the distance between the center of the cam roller 41 and the pivot point 28 of the radius link 27.

It will be noted that in the rotation of the radius link means and the cam means or cam slot 36 connected therewith, from open press position shown in Figure 2 to the closed press position prior to compression movement shown in Figure 3, that the high-speed portion 37 of the cam slot has been substantially at right angles to the direction of movement of the cam roller 41. This relation of the high-speed portion 37 of the cam means may be expressed in another manner as follows, that the high-speed portion of the cam means is substantially at right angles to the direction of the slide 41. As referred to above, the compression portion 38 of the cam slot 36 is at an angle to the high-speed portion 37 and consequently the compression portion of the cam slot 36 extends at a wedging angle to the direction of movement of the cam roller 41, shown in Figure 3, when the cam roller 41 reaches the end of the high-speed portion or the beginning of the compression portion of the cam means. This is also at the end of the high-speed movement of the jaw-carrying member 14 and head 13 or at the beginning of the compression movement of the head.

The compression portion 38 of the cam slot 36 therefore takes advantage of two methods of transforming the movement of the cam roller 41 into a powerful compression movement of the head 13 against the buck 12. One of these methods is by increasing the radius of the point of application on the cam means of the force of the cam roller 41. It will be noted that at the beginning of the compression movement the cam roller 41 contacts with the cam slot 36 at an increased radius from the frame pivot 28 on which it is pivoted so that at this increased radius the same unit of movement of the cam roller 41 will of itself produce reduced extent of rotation of the radius link 27 and the roller will instead exert an increased force upon the cam means and consequently on the head 13. Positioning the compression portion 38 of the cam slot 36 at a slight or wedging angle to the direction of movement of the cam roller 41 when this portion of the cam is engaged by the cam roller, brings about an even greater reduced extent of rotation of the cam means and radius links 27 for a unit movement of the cam roller 41 thereby further increasing the compression force exerted by the piston and the cam roller upon the radius links 27 and consequently upon the head or jaws also. This compression movement of the cam roller 41 working in the compression portion 38 of the cam slot 36 may also be described as a wedging connection inasmuch as the cam roller 41 exerts its pressure against an inclined cam slot 38 along which it moves and wedging the cam means or the arm 35 in a counter-clockwise direction which is transmitted through the radius links 27 and the jaw-carrying member 14 to the head 13.

It is obvious that the jaw or press head and buck compression may be increased merely by changing the angle of the compression portion 38 of the cam slot 36 so that it more nearly approaches the direction of movement of the cam roller 41 during the compression movement of the head 13 or when the cam roller engages this

portion of the cam which may be expressed also as a lessening of the angle between the direction of movement of the cam roller 41 or of the slide 47 during the compression movement of the head 13.

5 A mechanical advantage ratio changing means is therefore provided so that the first short portion of the stroke of the piston 45, say less than approximately half of the stroke, is utilized to 10 close the press head through the operation of the cam way 37, whereupon the angular portion 36 in the cam changes the ratio of the piston stroke to the press head travel, whereupon all 15 the remaining portion of the piston stroke is utilized to move the head through the short distance required to compress the pad and work on the buck. This ratio changing means acts during the motor stroke to utilize a minimum portion of 20 the stroke of the motor to close the press and save the major portion of the stroke to produce jaw compression.

The mounting of the jaw-carrying member 14 upon the frame 10, as shown particularly in Figure 6, provides a plurality of horizontally spaced compound motion pivots 24 upon the jaw-carrying member 14-31. A pair of spaced radius links 25 and 27 are provided on either side of the bearings 23 so that the flanges 31 of the jaw-carrying member swing between the pairs of spaced radius links 25 and 27 thereby producing 30 a rigid and wobble-proof construction for the member. This construction also provides a three point frame mounting for the jaw-carrying member 14 upon the frame pivots 26 in the sides of the frame and on the frame pivot 28 carried by 35 the central bearing 29, thereby setting up a plurality of frame pivots for the jaw-carrying member. A rigid mounting for the radius link means and consequently for the jaw-carrying member 40 14 results, which assists materially in reducing wobble or weaving between the jaws due to looseness or clearance in any of the bearings which support the jaw-carrying member. The flanges 31 carried by the jaw-carrying member 14 enable 45 such three point suspension of the jaw-carrying member without sacrificing any of the rigidity of the member 14.

The three point suspension or pivoting of the press frame 14, 31 shown in Figure 6 may have 50 the radius links 25 and 27 anchored to each or any of the frame pivots 26, 28 or to each compound motion pivot 24 by pinning, keying or any other method. With the radius links fixed to their pivots, the mounting for the jaw-carrying member 14, 31 is more rigid than any other and 55 the various pivots 24, 26, 28 with the radius links 25 and 27 together form a crank shaft construction. The frame pivots 26, 28 may however, as an alternative construction be fixed to the frame 60 and the compound motion pivots 24 be fixed to the hubs or bearings 23 on the jaw-carrying member 14, 31. In this construction the radius links 25 and 27 are free to turn on the pivots.

What is claimed is:

65 1. A garment or ironing press comprising co-acting press jaws, a jaw-carrying member to which one of the jaws is attached, radius link means pivotally carrying the jaw-carrying member on a frame pivot, guide means directing the movement of the jaw-carrying member at a 70 point spaced from the radius link means connection therewith, and operating means to open and close the press including mechanical advantage ratio-changing means connected with the radius 75 link means to apply pressure thereto initially at

a short radius for rapid closing of the press and subsequently at a greater radius for jaw compression.

2. A garment or ironing press comprising co-acting press jaws, a jaw-carrying member to 5 which one of the jaws is attached, radius link means pivotally carrying the jaw-carrying member on a frame pivot, guide means directing the movement of the jaw-carrying member at a point spaced from the radius link means connection 10 therewith, an arm connected with the radius link means, and operating means to open and close the press including means engaging the arm at a short radius for rapid closing of the press and at a longer radius for jaw compression. 15

3. A garment or ironing press comprising co-acting press jaws, a jaw-carrying member to which one of the jaws is attached, radius link means pivotally carrying the jaw-carrying member, means to guide the jaw-carrying member at 20 a point spaced from the pivotal connection of the radius link means therewith, cam means carried by the radius link means, and operating means to open and close the press including mechanical advantage ratio-changing means engaging 25 the cam means which rapidly closes the press but slowly produces jaw compression.

4. A garment or ironing press comprising a frame, coacting press jaws, a jaw-carrying member to which one of the jaws is attached, means 30 to guide the movement of the end of the jaw-carrying member, a bell crank one end of which provides a radius link means pivoted on the frame and connected to the jaw-carrying member at a point spaced from the guide means, cam means 35 formed in the other arm of the radius link means, and operating means including means engaging the cam means to open and close the press.

5. A garment or ironing press comprising co-acting press jaws, an upright jaw-carrying member to which one of the jaws is attached and the lower end of which terminates under the jaws, radius link means pivotally connected to the jaw-carrying member below the jaws, means controlling the movement of the jaw-carrying member at a point spaced from the radius link connection therewith, cam way means formed in the radius link means, the cam way means having a rapid-movement portion and a slow movement pressure portion, and operating means to open 50 and close the press including roller means running in the cam way means. 45

6. A garment or ironing press comprising co-acting press jaws, a jaw-carrying member to which one of the jaws is attached, radius link 55 means carrying the jaw-carrying member upon a frame pivot, cam means operatively connected to the radius link means, operating means to open and close the press including means movable adjacent to the frame pivot and engaging the 60 cam means, the cam means having a high-speed portion adjacent the frame pivot and disposed to swing substantially at right angles to the direction of movement of the operating means during the period the operating means is in contact with this portion of the cam means for rapid closing of the head, and a pressure portion at an angle to the high speed portion and extending at a wedging angle to the direction of movement of the operating means when engaged thereby to 70 obtain jaw compression. 65

7. A garment or ironing press comprising co-acting press jaws, a jaw-carrying member to which one of the jaws is attached, radius link means carrying the jaw-carrying member upon 75

- a frame pivot, guide means directing the movement of the jaw-carrying member at a point spaced from the radius link means connection therewith, cam way means formed in an arm joined to the radius link means, operating means to open and close the press including cam follower means movable adjacent to the frame pivot and within the cam way means, the cam way means having a high-speed portion adjacent the frame pivot and disposed to swing substantially at right angles to the direction of movement of the operating means during the period the operating means is in contact with this portion of the cam way means for rapid closing of the head, and a pressure portion at an angle to the high-speed portion and extending at a wedging angle to the direction of movement of the operating means when engaged thereby to obtain jaw compression.
8. A garment or ironing press comprising co-acting press jaws, a jaw-carrying member to which one of the jaws is attached, radius link means carrying the jaw-carrying member upon a frame pivot, cam means operatively connected to the radius link means, operating means to open and close the press including means movable substantially in a straight line adjacent to the frame pivot and engaging the cam means, the cam means having a high-speed portion adjacent the frame pivot and disposed to swing substantially at right angles to the direction of movement of the operating means during the period the operating means is in contact with this portion of the cam means for rapid closing of the head, and a pressure portion at an angle to the high-speed portion and extending at a wedging angle to the direction of movement of the operating means when engaged thereby to obtain jaw compression.
9. A garment or ironing press comprising co-acting press jaws, a jaw-carrying member to which one of the jaws is attached, radius link means pivotally carrying the jaw-carrying member upon a frame pivot, guide means controlling the movement of the jaw-carrying member at a point spaced from the radius link connection therewith, an arm operatively connected to the radius link means, a cam slot in the arm, operating means including means movable adjacent to the frame pivot and engaging in the cam slot, the cam slot having a high-speed portion adjacent the frame pivot and disposed to swing substantially at right angles to the direction of movement of the operating means during the period the operating means is in contact with this portion of the cam slot for rapid closing of the head, and a pressure portion at an angle to the high-speed portion and extending at a wedging angle to the direction of movement of the operating means when engaged thereby to obtain jaw compression.
10. A garment or ironing press comprising a frame and coacting press jaws, a jaw-carrying member to which one of the jaws is attached, pivot means in the frame, radius link means mounted upon the pivot and carrying the jaw-carrying member, guide means directing the movement of the jaw-carrying member at a point spaced from the radius link connection therewith, at least one arm connected with the radius link means, cam means on the arm, force applying means engaging the cam and movable from a point adjacent the pivot to a point distant therefrom, means to guide the force applying means in a straight line in its movement, and operating means to open and close the press including means for actuating the force applying means.
11. A garment or ironing press comprising a frame and coacting press jaws, a swingable jaw-carrying member to which one of the jaws is attached, pivot means in the frame, radius link means mounted upon the pivot means and carrying the jaw-carrying member, guide means directing the movement of the jaw-carrying member at a point spaced from the radius link connection therewith, arms connected with the radius link means, a cam slot in each arm, force applying means engaging within the cam slots and movable from a point adjacent the pivot to a point distant therefrom, and operating means to open and close the press including means for actuating the force applying means.
12. A garment or ironing press comprising a frame and coacting press jaws, a swingable jaw-carrying member to which one of the jaws is attached, pivot means in the frame, radius link means mounted upon the pivot means and carrying the jaw-carrying member at a point between its ends, arms connected with the radius link means, a cam slot in each arm, force applying means engaging within the cam slots and movable therein, a slide attached to the frame to guide the force applying means from a point adjacent the pivot to a point distant therefrom, fluid motor means cooperating with the slide to drive the force applying means to close the press, and spring means to open the press.
13. A garment and ironing press comprising a frame, coacting press jaws, a jaw-carrying member including spaced apart uprights to which one of the jaws is attached, at least three spaced frame pivots in axial alignment, two pairs of spaced radius links carried on the frame pivots, the jaw-carrying member being pivotally mounted upon and between each pair of spaced radius links so the latter swing between the spaced apart uprights, means to guide the lower end of the jaw-carrying member, and operating means connected with the radius links to open and close the press.
14. A garment and ironing press comprising a frame, coacting press jaws, an upright jaw-carrying member to which one of the jaws is attached, at least three spaced frame pivots in axial alignment under the jaws, two pairs of spaced radius links carried on the frame pivots, the jaw-carrying member being pivotally mounted upon and between certain of the spaced radius links, means to guide the lower end of the jaw-carrying member, arms extending from one of each pairs of the spaced radius links, and operating means to open and close the press including means engaging the arms to close the press.

ERNEST DAVIS.
